(57) CLAIM

The ornamental design for a cloud shaped tray, as shown and described.

DESCRIPTION

FIG. 1 is a top perspective view from above of a cloud shaped tray;

FIG. 2: is a bottom perspective view thereof;

FIG. 3: is a front side thereof;

FIG. 4: is a back side thereof;

FIG. 5: is a side view thereof;

FIG. 6 is a further side view thereof which is opposite the side view of FIG. 5;

FIG. 7: is a further top view thereof; and,

FIG. 8 is a bottom view thereof.

The portions of the tray shown in regular broken lines including the round recesses visible from the bottom views form no part of the claimed design.

1 Claim, 3 Drawing Sheets
